UNITED STATES PATENT OFFICE.

JOHN P. GERAGHTY, OF JERSEY CITY, NEW JERSEY.

LOCKING DEVICE FOR AUTOMOBILES.

1,343,049.

Specification of Letters Patent.

Patented June 8, 1920.

Application filed May 3, 1919. Serial No. 294,622.

To all whom it may concern:

Be it known that I, JOHN P. GERAGHTY, a citizen of the United States, and a resident of Jersey City, in the county of Hudson and State of New Jersey, have invented 5 a new and Improved Locking Device for Automobiles, of which the following is a full, clear, and exact description.

The object of the invention is to provide 10 a new and improved locking device for automobiles and similar vehicles and arranged to prevent unauthorized persons from starting and running the motor thereby preventing such persons from stealing the vehicle. 15 Another object is to provide means within the hood inclosing the motor to prevent starting of the motor and to provide a locking means for locking the hood to prevent unauthorized persons from gaining access 20 to such means with a view to prevent starting of the motor. Another object is to provide a plurality of devices for rendering various parts of the motor inoperative to prevent even highly skilled, unauthorized 25 experts from running off with the car even if one of the said devices is rendered operative owing to the remaining devices being still in inoperative position thereby preventing starting of the motor. 30 With these and other objects in view, the invention consists of certain novel features of construction as hereinafter shown and described and then specifically pointed out in the claims.

35 A practical embodiment of the invention is represented in the accompanying drawings forming a part of this specification, in which similar characters of reference indicate corresponding parts in all the views.

40 Figure 1 is a longitudinal sectional elevation of the forward end of an automobile provided with the improved locking device, the motor being shown in dotted lines, the section being taken on the line 1—1 of 45 Fig. 2;

Fig. 2 is a sectional plan view of the same on the line 2—2 of Fig. 1;

Fig. 3 is an enlarged side elevation of 50 one of the interior locking devices for locking the hood to the chassis;

Fig. 4 is a cross section of the same on the line 4—4 of Fig. 3;

Fig. 5 is an enlarged side elevation of the device for holding in a closed position the 55 butterfly valve arranged in the connection

between the carburetor and the inlet manifold of the motor;

Fig. 6 is an enlarged face view of the switch interposed in the electric igniting system to break the ignition circuit whenever it is desired to render the motor inoperative; 60

Fig. 7 is an enlarged sectional side elevation of the permutation lock for locking the several devices when in operative position; 65

Fig. 8 is a face view of the same.

On the chassis 10 of an automobile or other vehicle is mounted the usual motor 11 inclosed within a hood 12 adapted to be 70 locked to the chassis by interior locking devices 15, preferably two on each side, as shown in Figs. 1 and 2, but alike in construction so that it suffices to describe but one in detail. On the inner face of the hood 75 12 is secured a keeper 16 adapted to be engaged by a bolt 17 mounted to slide in a guideway 18 attached to the chassis 10. The bolt 17 is normally out of engagement with the keeper 16 and the bolt is attached to or 80 forms part of a longitudinally extending rod 19 provided near its rear end with a pivot 20 connected by a link 21 with an arm 22 secured on a shaft 23 extending transversely and journaled in suitable bearings 85 24 attached to the transverse partition 25 at the rear end of the hood 12, the partition forming part of the dashboard 26. The shaft 23 is provided with an arm 30 pivotally connected with the forward end of a 90 link 31 extending rearwardly through the partition 25 and the dashboard 26 and through the footboard 32 forming part of the dashboard 26. The rear end of the link 31 is pivotally connected with a pedal 33 95 pivoted at 34 to the footboard 32 and under the control of the operator in charge of the automobile. A spring 35 attached to the under side of the footboard 32 is connected with a collar 36 held on the link 31 to normally hold the latter in rearmost position with the pedal 33 standing upright, as plainly indicated in Figs. 1 and 2. Each of the rods 19 is mounted to slide in the lower portions of the bearings 18 to insure 100 proper engagement of the bolts 17 with the keepers 16 whenever the pedal 33 is pushed forward and a rocking motion is given to the shaft 23 which by the arms 22 and links 21 causes a forward sliding movement of 110

the rods 19 and the bolts 17 thus engaging the latter with the keepers 16 to lock the hood 12 in closed position thereby preventing access to the motor 11.

5 Within the hood 12 are arranged a plurality of devices controlled from the shaft 23 and connected with different members of the motor 11 for rendering the latter inoperative by each of the said devices. As shown in
10 the drawings, use is made of a shut-off valve 40 arranged in the pipe 41 connecting the reservoir 42 with the carburetor of the motor, it being understood that this valve 40 is normally in open position but is moved
15 into closed position whenever the operator presses the pedal 33 in a forward direction. It is understood that when the valve 40 is closed the supply of the motor fuel is cut off and hence the motor cannot be run. The
20 valve 40 is provided with an arm 42 connected by a link 43 with an arm 44 secured on the rock shaft 23 and hence when the latter is rocked on pressing the pedal 33 the valve 40 is moved into closed position for
25 the purpose mentioned.

The butterfly valve 50 arranged in the pipe 51 connecting the carburetor with the intake manifold 52 of the motor is provided with a rock shaft 55 on one outer end of
30 which is secured the usual arm 56 connected with the usual controlling mechanism under the control of the operator for moving the butterfly valve 50 into open or closed position. When the automobile is stopped the butterfly valve 50 is usually moved into
35 closed position by the operator correspondingly manipulating the actuating device for the butterfly valve, and in order to hold the butterfly valve locked when in closed position use is made of an arm 60 fulcrumed on a bracket 61 attached to the flanges 62, 63 connecting the pipe 51 with the manifold 52. The free end of the arm 60 is in the form of a fork 65 adapted to straddle the arm 56
40 thus holding the latter against movement thereby preventing opening of the butterfly valve 50, as will be readily understood by reference to Fig. 5. The arm 60 is pivotally connected by a link 66 with an arm 67 attached
45 to the rock shaft 23 so that when the latter is rocked as previously explained the arm 60 is swung forward into locking engagement with the arm 56 of the butterfly valve 50 thus holding the latter locked when in closed
50 position. It is understood that when the butterfly valve 50 is locked in closed position the motor 11 cannot be started and run.

Another device in the form of a switch is provided for breaking the ignition circuit
60 of the motor 11 thus rendering the latter inoperative. For this purpose use is made of a switch bar 70 mounted to slide up and down in suitable bearings 71 arranged on the front face of the partition 25, and the lower
65 end of this switch bar 70 is provided with a

slot 72 engaged by a pin 73 held on an arm 74 attached to the shaft 23. Normally the switch bar 70 is in uppermost position but when the pedal 33 is pressed and the shaft 23 is rocked as previously explained then the 70 arm 74 imparts a downward sliding movement to the switch bar 70. The switch bar 70 is provided with a crossbar 79 of an insulating material and on which are secured a number of spring contacts 80 corresponding to the number of motor cylinders. The spring contacts 80 normally engage contacts 81 mounted on the partition 25 and connected by wires 82 with a timer connected with a source of electrical energy. The spring contacts 80 are connected by wires 83 with the spark plugs of the engine cylinders. It will be noticed that when the parts are in a normal position, as shown in Figs. 1, 2 and 6, then the wires 80 are electrically connected with the wires 83 to insure proper ignition of the explosive mixture in the motor cylinders in the usual manner, but when the pedal 33 is pressed forward and a rocking movement is given to the shaft 23 then the switch bar 70 is moved downward whereby the spring contacts 80 move out of engagement with the contacts 81 thus breaking the ignition circuits for the several motor cylinders and thereby rendering the motor 95 inoperative. Normally the several devices are in inoperative position and are only moved into operative position on the operator pressing the pedal 33 in a forward direction against the tension of the spring 35, 100 it being understood that when this takes place the hood 12 is locked, the valve 40 is moved into closed position, the butterfly valve 50 is locked against movement, and the ignition circuits for the several motor 105 cylinders are broken. Hence, the motor is rendered inoperative and the hood 12 is locked by the interior locking device thus preventing access to the motor and the several devices above referred to.

In order to hold the bolts 17 in locking position, the valve 40 in closed position, the arm 60 in locking position, the switch bar 70 in circuit breaking position and the pedal 33 in forward position, use is made of 115 a locking bolt 90 adapted to engage an aperture 91 formed in the upper end of the switch bar 70. The bolt 90 is mounted to slide in a casing 92 mounted on the partition 25 and the dashboard 26, and the bolt 120 90 is pressed on by a spring 93 to normally hold the bolt in rearmost position, that is, out of engagement with the switch bar 70. The rear end 94 of the bolt 90 projects beyond the face of the dashboard 26 and is 125 adapted to be engaged by a locking arm 95 pivoted on a bracket 96 attached to the face of the dashboard 26. Immediately after a forward swinging movement has been given to the pedal 33, as above de- 130

scribed, the operator swings the locking arm 95 upward into engagement with the rear end 94 of the bolt 90 thus pushing the latter forward and into engagement with the aperture 91 of the switch bar 70 now in lowermost position, thus locking the switch bar in this position. It is understood that when the bolt 90 engages the aperture 91 the switch bar 70 is locked in lowermost position, and as this switch bar 70 is connected with the rock shaft 23 the latter and the several devices connected therewith, including the pedal 33, are held in locked position with the several devices in operative position.

When the arm 95 is swung upward its free end 97 engages a locked frame 100 attached to the upper portion of the dashboard and this frame 100 forms a part of a permutation lock of any approved construction, but preferably of the construction more fully shown and described in the application for Letters Patent of the United States, No. 291,028, filed by me on April 18, 1919. The permutation lock is provided with a locking slide 101 adapted to engage the free end 97 of the locking arm 95 to lock the latter in closed position, and the said locking slide 101 is controlled by tumblers 102 mounted to turn on the frame 100 and provided with the usual letters, numerals and other characters (see Fig. 8) to permit of setting the tumblers to any desired combination and which combination is only known to the operator in charge of the vehicle and hence unauthorized persons cannot open the lock and release the arm 95. When the operator in charge desires to start the vehicle, he sets the tumblers 102 to the predetermined combination thus unlocking the arm 95 and allowing the same to swing downward into unlocking position thus releasing the bolt 90. The latter now returns by its spring 93 to rearmost position thus disengaging the switch bar 70. When this takes place the several parts return to their normal inoperative position by the action of the spring 35 connected with the pedal link 31. It is understood that when this takes place the hood 12 is unlocked, the valve 40 moves into open position, the arm 60 disengages the arm 56 of the butterfly valve 50, the spring contacts 80 move into engagement with the contacts 81 thus closing the ignition circuits, and the pedal 33 returns to normal upright position.

Having thus described my invention, I claim as new and desire to secure by Letters Patent:—

1. In a motor driven vehicle, a motor, a hood inclosing the motor, a locking device within the hood for locking the latter, a plurality of motor controlling devices arranged within the hood and connected with different members of the motor for render-

ing the latter ineffective, a rock shaft within the hood and connected with the said hood locking device and the said plurality of motor controlling devices to simultaneously actuate the same, operating means controlled by an operator and connected with the said shaft to actuate the same, and locking means controlled by an operator and connected with the said shaft to lock the latter against rotation after the said hood locking device and the said plurality of motor controlling devices have been moved into operative position. 70

2. In a motor driven vehicle, a motor, a hood inclosing the motor, a rock shaft arranged within the said hood, operating means under the control of an operator and located outside of the hood, the said operating means being connected with the said shaft to rock the latter, a locking device connected with and actuated from the said shaft, and arranged within the hood for locking the latter against opening, a plurality of devices arranged within the hood and connected with different members of the motor for rendering the latter ineffective, the said plurality of devices being connected with and actuated from the said shaft, and a lock arranged outside of the hood and having a member adapted to pass into the hood to lock the said rock shaft against turning after the rock shaft is turned in one direction and the hood lock and the plurality of devices have been moved into operative position. 85

3. In a motor driven vehicle, a motor, a hood inclosing the motor, a locking device within the hood for locking the latter, a plurality of motor controlling devices arranged within the hood and connected with different members of the motor for rendering the latter ineffective, a rock shaft within the hood and connected with the said hood locking device and the said plurality of motor controlling devices to simultaneously actuate the same, a pedal arranged outside of the hood and connected with the said shaft to rock the latter in one direction, spring means for returning the shaft and pedal to normal position, and a manually controlled locking means arranged outside of the hood and under the control of an operator, the said locking means being adapted to lock the rock shaft against rotation after the pedal has been actuated and the said hood locking device and the plurality of motor controlling devices have been moved into operative position. 100

4. In a motor driven vehicle, a motor, a hood inclosing the motor, a locking device 105 within the hood for locking the latter, a plurality of motor controlling devices arranged within the hood and connected with different members of the motor for rendering the latter ineffective, a rock shaft within the 110

hood end connected with the said hood locking devices and the said plurality of motor controlling devices to simultaneously actuate the same, a spring-pressed pedal arranged outside of the hood and connected with the said shaft to rock the latter, and a manually controlled locking device arranged outside of the hood and including a bolt, one of the said motor controlled devices having an apertured member adapted to be engaged by the said bolt to lock the rock shaft against turning after the said pedal has been pressed by an operator and the said hook locking device and the said motor controlling devices have been moved into operative position.

5. In a motor driven vehicle, a motor, a hood inclosing the motor, a locking device within the hood for locking the latter against opening, a motor controlling device arranged within the hood and connected with the said motor to render the latter inoperative, the said controlling device being provided with a bar having an aperture, a 10 rock shaft arranged within the hood and connected with the said hood locking device and with the said bar to simultaneously move the hood locking device into locking position and the said motor controlling device into operative position, means for rocking the said shaft, and a manually controlled lock arranged outside of the hood

and provided with a bolt adapted to engage the aperture in the bar after the hood is locked and the motor is rendered inoperative. 35

6. In a motor driven vehicle, a hood inclosing the motor, a locking device within the hood for locking the latter against opening, a device for shutting off the fuel supply to the motor and arranged within the said hood, a device within the hood for rendering inoperative the valve connecting the carburetor with the inlet manifold of the motor, a device arranged within the hood 40 for breaking the ignition circuit of the motor, an actuating device under the control of the operator in charge of the vehicle and connected with the said devices within the hood to move the said devices into operative 45 position, a permutation lock for locking the said several devices in operative position, the said permutation lock having a spring-pressed locking bolt projecting through the dashboard of the vehicle, a locking frame 50 mounted on the dashboard, a locking arm adapted to engage the bolt to move the latter into locking position, the said locking arm being adapted to engage the said frame, a locking plate engaging the said locking 55 arm and mounted on the said frame, and tumblers adapted to lock the said locking plate. 60

JOHN P. GERAGHTY.
